(57) CLAIM

The ornamental design for tableware, as shown and described.

DESCRIPTION

FIG. 1 is a top perspective view of the tableware according to a first embodiment;

FIG. 2 is a front elevation view thereof;

FIG. 3 is a rear elevation view thereof;

FIG. 4 is a left elevation view thereof;

FIG. 5 is a right elevation view thereof;

FIG. 6 is a top view thereof; and,

FIG. 7 is a bottom view thereof.

The broken lines shown in the figures are included for the purpose of illustrating portions of the tableware that form no part of the claimed design.

1 Claim, 5 Drawing Sheets(56)
